United States Patent Office

Des. 221,808
Patented Sept. 7, 1971

221,808

BOAT

Terry J. Simpkins, Dublin, Ohio, assignor to
AMF Incorporated

Filed May 4, 1970, Ser. No. 22,793

Term of patent 14 years

Int. Cl. D12—06

U.S. Cl. D71—1

FIG. 3

FIG. 4

FIG. 5

FIG. 1 is a side elevational view of a boat showing my new design.

FIG. 2 is a top plan view.

FIG. 3 is a bottom plan view.

FIGS. 4 and 5 are rear and front elevational views, respectively.

I claim:

The ornamental design for a boat, substantially as shown.
